RAILWAY TRAFFIC CONTROLLING
APPARATUS

John M. Pelikan, Pittsburgh, Pa., assignor to The
Union Switch & Signal Company, Swissvale,
Pa., a corporation of Pennsylvania

Application December 17, 1940, Serial No. 370,433

16 Claims.

(Cl. 246—26)

My invention relates to railway traffic controlling apparatus and more particularly to a manual block system employing reversible track circuits in which all of the control operations are performed by means of track circuits without the necessity for any control line wires. My invention is accordingly well adapted to a system of single track, two-direction signaling where the use of control line wires is undesirable or impractical. My present invention is an improvement on the invention disclosed in my co-pending application Serial No. 367,352, filed on November 27, 1940, for Railway traffic controlling apparatus, now Patent No. 2,251,689, issued August 5, 1941.

One object of my invention is to provide a coded track circuit system for two-direction signaling on a single track without employing control line wires. Another object of my invention is to provide a system of the above character which provides broken-down rail joint protection and in which traffic cannot be falsely set up in both directions at the same time by stray currents. Other objects, purposes and features of my invention will be apparent from the description which follows.

I accomplish the foregoing objects by providing each track circuit with two polarized code following track relays, one at each end of the associated track circuit, so arranged and connected that each relay operates as a track relay only for its proper direction of traffic. I establish traffic direction in accordance with the polarity of the coded track current and employ directional stick relays for permitting following traffic movements and for preventing the set-up of conflicting routes. By employing code, I provide a plurality of signal indications which permit following moves through the single track stretch to be easily and safely made.

I shall describe one form of apparatus embodying my invention, and shall then point out the novel features thereof in claims.

Figs. 1a and 1b of the accompanying drawings when placed end to end with Fig. 1a at the left, are a diagrammatic view showing a stretch of single track railroad equipped with apparatus embodying my invention.

Referring to the drawings, the stretch of single track between the two passing sidings at locations D and E is divided by means of insulated rail joints 2 into a number of track circuits such as 5T, 4T, 7T, and 8T. Entry into each of these track circuits is governed by a wayside signal located at the entering end of the track circuit

for the particular traffic direction. At F is a cut-section location which merely subdivides the section of track between signals 4 and 8 into two track circuits for the purpose of providing improved track circuit operation.

Each eastbound track circuit is provided with an eastbound code following track relay at the entering end designated with a prefix corresponding to the associated track circuit, and with a normally disconnected source of track circuit current at the leaving end. Each westbound track circuit includes the rails of the eastbound track circuit but is provided with its own westbound code following track relay at the entering end for that direction and with a normally disconnected source of current at the leaving end. The track relays are of the biased two-position polarized type which pick up when energized with current of one polarity but which remain in the released position to which they are biased when current is discontinued or when current of the other polarity is supplied thereto. The purpose in maintaining the track circuit sources normally disconnected is to economize track battery, these sources becoming connected in response to the action taken by the operator or operators in setting up the apparatus for a traffic move in one or the other direction over the single track stretch.

At each signal location there is a suitable code transmitter CT which may be of the motor driven type and which supplies a 120 or 75 code by intermittently closing certain contacts designated as 120 and 75, respectively, on the drawings at the rate of 120 or 75 times per minute. Looking at location E, for example, and signal 10 which is shown at stop, the coder CTE which is energized from a source of current having the terminals B—C causes the flashing

operation of the eastbound flashing relay 10EFR at a rate of either 120 or 75 times per minute, depending on the energized or deenergized condition of the home relay 10H for signal 10 which controls contact 42 in the circuit for relay 10EFR. Since the signal 10 is at stop, the home relay 10H will be deenergized and the back point of contact 42 will be closed so that relay 10EFR operates at 75 code, it being assumed that the traffic lever 11 has been moved to its normal or N position for an eastbound traffic move so that its N contact is closed and the circuit for relay 10EFR is therefore complete. Should signal 10 be occupying either the caution or the clear position, the front point of contact 42 of relay 10H would then be closed so that relay

10EFR would be operating at a rate of 120 times per minute. In order to simplify the disclosure as much as possible and make the circuits easy to follow, contact N of traffic lever 11, contacts 120 and 75 of coder CTE, as well as contact 42 of relay 10H are shown removed from the apparatus by which they are operated, but in each case these contacts are clearly identified by the function which operates them. The same is also true of other contacts in the drawings, which for simplicity are identified by the relay which operates them rather than being shown in physical proximity to such relay.

Coding of the track circuit current itself is performed by the associated flashing relay for the established traffic direction, and response of the track relay to this code causes operation of certain decoding relays which control the signal indication and which code the adjoining track circuit so that relaying of the code will automatically continue from track circuit to track circuit until the headblock signal location for the desired traffic direction is reached. At location E, coding of the track circuit 8T is performed over the front point of contact 6 of relay 10EFR which periodically connects the track battery TB across the rails.

Looking next at location 7-8, the code following action of the eastbound track relay 8ETR in following 120 code will maintain the distant relay 7-8DR energized by virtue of the resonated transformer-rectifier circuit which is tuned to pass impulses of 120 code but not 75 code. The energizing circuit for relay 7-8DR may be traced from one terminal B, over the front point of code following contact 12 of relay 8ETR, front contact 13 of the check relay 7-8CK, wire 14, and front contact 15 of the home repeater relay 8EHP, to the tuned transformer and terminal C. Relay 7-8DR has a sufficient release interval to bridge the impulses of the 120 code. The check relay 7-8CK will be maintained energized on either 120 or 75 code over an obvious circuit which includes the back point of the periodically operating contact 12 of relay 8ETR and the constantly closed back contact 16 of the opposing track relay 7WTR.

Relay 8EHP is merely a repeater of the home relay 8EHR and is maintained energized over the front contact 17 of the latter relay. Relay 8EHR is maintained energized on either 120 or 75 code over the front point of contact 12 of relay 8ETR and front contact 13 of relay 7-8CK. The sequence of operations beginning with the code following action of relay 8ETR is accordingly as follows: pick-up of relay 7-8CK (if this relay has not previously been picked up); pick-up of relay 8EHR; pick-up of relay 8EHP; and finally, pick-up of relay 7-8DR. It will be understood that all of these relays (except 7-8DR which responds only to 120 code) are so designed as to remain picked up whether the code which is effective in the track circuit 8T is 120 or 75. The home relay 7WHR for the west-bound signal 7 will obviously be deenergized because its circuit will be open at the front point of contact 16 of the westbound track relay 7WTR. Accordingly, the repeater 7WHP will also be deenergized. The westbound track relay 8WTR at the other end of track circuit 8T will not be operated by the discharge of any stored energy in the track resulting from the track circuit code because such energy will be of wrong po-

larity for pick-up of relay 8WTR and will merely aid in maintaining this relay released.

Under the above conditions, signal 7 will be at stop, its red lamp being illuminated over an obvious lighting circuit which includes the terminals EN and EB of a suitable lighting source and back contact 18 of relay 7WHP. If the code is 120 (so that relay 7-8DR is up) signal 8 will be at clear, with the green lamp energized over the front point of contact 19 of relay 7-8DR and the front point of contact 20 of relay 8EHP. If the code is 75 so that relay 7-8DR is released, signal 8 will be at caution, as shown, with the yellow lamp illuminated over the back point of contact 19 and the front point of contact 20.

At the location 7-8, I also employ directional stick relays 8ESR and 7WSR but since the operation of these relays comes into play only during the passage of a train through the section, this operation will be described hereinafter.

I shall next describe how the code following operation of track relay 8ETR causes code to be relayed into section 7T and into the remaining sections to the left for setting up an eastbound route over the single track stretch.

If the track relay 8ETR is following 120 code, then this same code will be relayed into track circuit 7T by virtue of the operation of flashing relay 8EFR. This relay has a 120 code operating circuit which includes one terminal B, wire 21, contact 120 of coder CT9-10, wire 22, front point of contact 23 of relay 8EHP, and the winding of relay 8EFR, to the other terminal C of the source. This 120 code operating circuit is effective whether relay 8ETR is following 120 or 75 code because relay 8EHP will be picked up in either case, thus completing the circuit. If, however, a train is occupying the track circuit 8T, then the operating circuit for relay 8EFR will include contact 15 of coder CT9-10, front contact 24 of directional stick relay 8ESR, and the back point of contact 23 of relay 8EHP which will now be deenergized. The directional stick relay 8ESR will have been picked up as a result of the entry of the train into track circuit 8T, as will be explained hereinafter, thus closing the 75 code circuit for relay 8EFR.

The periodic closing of front contact 25 of relay 8EFR will impress either 120 or 75 code from the track battery TB across the rails of track circuit 7T. Since location F is a cut section location, the 120 or 75 code will be repeated into the adjoining track circuit 4T because of the code following response of the eastbound track relay 7ETR and the inclusion of front contact 26 of this relay in the code supply circuit for track circuit 4T. As a result, the eastbound track relay 4ETR will follow either 120 or 75 code, as the case may be. If the code is 120, the group of relays 4-5CK, 4EHR, 4EHP, and 4-5DR will all be energized, in the same manner as described for the corresponding relays at location 7-8. Accordingly, eastbound signal 4 will indicate proceed and westbound signal 5 will indicate stop.

Code will be relayed into track circuit 5T in an identical manner with that described for track circuit 7T, so that the eastbound track relay 5ETR will follow either 120 or 75 code according as the stretch of track between signals 4 and 8 is unoccupied or occupied, respectively.

At each end of the single track stretch I have provided a traffic lever having a normal position N for eastbound traffic and a reverse position R

for westbound traffic, these levers being designated by the reference numerals 1 and 11 at the ends D and E, respectively, of the stretch. At each of these two ends I have also provided a signal lever having a neutral position *n* in which no contacts are closed; a right-hand position *r* corresponding with eastbound traffic; and a left-hand position *l* corresponding with westbound traffic. These signal levers are designated as 2 and 9 at the ends D and E, respectively, of the single track stretch.

Having described the individual apparatus and its operation at the different locations, I shall now assume that with the stretch D—E in its normal or unoccupied condition as shown, it is desired to set up the apparatus for an eastbound traffic move. To do this, each of the traffic levers 1 and 11 is moved to the N position (unless the last movement was eastbound, in which case the traffic levers will already be occupying the N position), and the signal lever 2 is then moved to the *r* position. At the leaving end E of the stretch, relays 9CK, 9WHR, and 9DR will all be deenergized because the energizing circuit for each of these relays includes the reverse contact R of traffic lever 11 which is now open. Accordingly, the opposing signal L9 will indicate stop, its red lamp being lighted over the back contact 28 of relay 9WRH. The normal contact N of lever 11 will, as described hereinbefore, close the 75 code circuit for flashing relay 10EFR so that 75 code will be impressed on the track circuit 8T over the front point of contact 6 of relay 10EFR. The reason why 75 code and not 120 code is supplied to section 8T is that a train is shown occupying the section immediately in advance of the single track stretch D—E, so that signal 10 is at stop and its home relay 10H is deenergized.

From this point on, the sequence of operations up to the response of track relay 5ETR will be clear from the previous description. Track circuits 7T, 4T, and 5T will all be receiving 120 code; signal 4 will indicate proceed; and signal 8 will indicate caution (since 75 code has been assumed in the track circuit 8T due to the presence of a train just beyond location E). The opposing signals 7 and 5 will obviously be at stop.

Looking now at the entrance end D, the check relay 2CK will be picked up over a circuit which includes the normal contact N of traffic lever 1, the right-hand contact *r* of signal lever 2, and the back point of contact 29 of periodically operating relay 5ETR. Relay 2EHR will accordingly be picked up over the contacts N and *r* of levers 1 and 2, in series, front point of contact 29 of relay 5ETR, and front contact 30 of relay 2CK. Since relay 5ETR is responding to 120 code, the decoding relay 2DR will also be picked up so that the entering signal R2 will then indicate proceed, its green lamp being lighted over the front contacts 31 and 32 of relays 2EHR and 2DR, respectively, in series. Relay 1FR will, of course, not be flashing but will remain constantly deenergized since its energizing circuit will be open at the reverse contact R of traffic lever 1. It will be clear, therefore, that relay 5ETR will remain constantly connected across the rails, over the back contact 33 of relay 1FR. With the clearing of signal R2 by movement of the signal lever 2 to its *r* position, eastbound traffic may proceed into the single track stretch.

I shall next trace the progress of an eastbound train through the section, the traffic levers 1 and 11 having been placed at normal, signal lever 2 being to the right, and signal R2 indicating pro-

ceed. As the train enters the track circuit 5T, the track relay 5ETR becomes released, causing relays 2EHR and 2DR to release so that signal R2 goes to red. Relay 2CK will remain energized and the operator should then place the signal lever 2 in its neutral or *n* position in order to drop out relay 2CK so as to prevent any possibility of signal R2 becoming cleared after the train has vacated section 5T and the directional stick relay 4ESR has picked up.

When the train passes signal 4 which has been at green, directional stick relay 4ESR will pick up and will remain up thereafter until an opposing route is established. The pick-up of 4ESR occurs as follows. The opposing directional stick relay 5WSR is, of course, released and prior to the entry of the train into section 4T, relays 4EHR and 4EHP are both picked up. The shunting of track relay 4ETR will release 4EHR, but for a short interval thereafter, relay 4EHP will remain picked up because of its slow release interval. Accordingly, 4ESR will have a pick-up circuit which includes back contact 34 of 5WSR, back contact 35 of 4EHR, and front point of contact 36 of 4EHP. A stick circuit is now closed for relay 4ESR over back contacts 34 and 35 of relays 5WSR and 4EHR, wire 37, and front contact 38 of relay 4ESR. The subsequent release of relay 4EHP closes a second stick circuit for relay 4ESR over back point of contact 36 of relay 4EHP, wire 37, and front contact 38 of relay 4ESR.

The pick-up of 4ESR prepares a 75 code circuit for flashing relay 4EFR so that as soon as 4EHP releases, this flashing relay will be energized over the 75 code contact of coder CT4—5, front contact 39 of relay 4ESR and back contact 40 of relay 4EHP. The operation of relay 4EFR will begin the coding of the track circuit 5T at 75 code over the front point of contact 41 so that the response of relay 5ETR to this code as soon as the train vacates section 5T will cause signal R2 to go to yellow in order to permit a following train to enter the single track stretch during occupancy thereof by the first train.

During the time that the train occupies the sections 4T and 7T, relay 4ESR will remain picked up and relay 4EHR will remain released. Signal 4 will be at stop. As soon as the train fully vacates section 7T, the coding action of relays 7ETR and 4ETR, in turn, followed by pick-up of relays 4EHR and 4EHP will cause release of the stick relay 4ESR. Since relay 4ETR is following 75 code, relay 4EHP will be up and relay 4—5DR will be down, so that signal 4 will indicate yellow or caution at this time. The manner in which 75 code was supplied to section 7T when the train passed beyond signal 8 and shunted relay 8ETR will be clear from the description of the application of 75 code to section 5T when the train passed signal 4. That is, the pick-up of 8ESR and release of 8EHP causes flashing relay 8EFR to operate at 75 code and to supply this code to section 7T, whereupon it is relayed to the cut section 4T. Signal 8 will, of course, now be at stop.

Looking again at the signal 4 location, since relay 4EHP is now up, relay 4EFR will be following 120 code because it will be energized over the 120 code contact of coder CT4—5 and the front point of contact 40 of relay 4EHP. Accordingly, 120 code will be supplied to section 5T so that signal R2 will go to green, signal 4 being at yellow and signal 8 at red, with the train now wholly in section 8T.

When the train fully clears section 8T and occupies the adjoining section as shown in the drawings, 75 code will be supplied to section 8T because the flashing relay 10EFR will be energized over the back point of contact 42 of relay 10H (which is the home relay for signal 10 of the section now occupied by the train) and the 75 code contact of coder CTE. Operation of relay 8ETR on 75 code will pick up relays 8EHR and 8EHP so that signal 8 will go to yellow. The pick-up of 8EHP will drop out 8ESR and will change the rate of operation of 8EFR from 75 to 120 code so that 120 code will now be supplied to sections 7T and 4T, causing signal 4 to go to green. Since the train is now completely out of the single track stretch, an opposing or westbound route can be set up by reversing both traffic levers 1 and 11 to their R positions and placing signal lever 9 in its left-hand or l position.

Since the operations involved in setting up a westbound route and in the passage of a westbound train over the section are precisely the same as already described for an eastbound movement except involving the corresponding westbound relays and signals, these operations will be clear without further description.

Summarizing briefly the operations which take place, moving the traffic lever at the new exit end of the stretch to the position corresponding to the desired traffic direction causes code to be applied to the first track circuit at the new exit end, which code is relayed progressively over the intervening track circuits to cause operation of the code following track relay at the new entering end of the stretch. If now both the traffic lever and the signal lever at the entering end are placed in the position corresponding to the desired traffic direction, the entering signal will clear to permit entry of the train into the single track stretch. The opposing signals will be held at stop by virtue of the position of the traffic lever at the new exit end, following movements being permitted by means of directional stick relay control which establishes proper permissive signal indications in the rear of the train. Once a train has entered the single track stretch, the traffic direction cannot be reversed by manipulation of the traffic levers, until such time as the train has fully cleared the stretch. A back-up move can, however, be permitted by proper movement of the traffic lever at that end of the stretch which serves as the exit for the back-up move. For example, an eastbound train occupying the section 4T may back up and leave the single track stretch at location D provided that lever 1 is first moved to the R position which causes code to be applied to section 5T by virtue of the code operation of relay 1FR.

It will be apparent from the foregoing that I have provided a two-direction single track system of the A. P. B. type in which coded polarized current is used for establishing traffic direction in accordance with current polarity and for selecting the signal indications. Operation of a pair of traffic levers, one at each end of the single track stretch, and a signal lever at the entering end, clears the signals for a train movement through the stretch and permits following trains to enter but prevents any opposing move or a change in the established direction until the single stretch is completely vacated. The polarity of adjoining track circuits, though shown alike in the drawings, for simplicity, may be staggered for the purpose of providing broken-down rail

joint protection. Because of the use of polarity code, opposing signals cannot be cleared at the same time through the medium of stray currents, or otherwise. Moreover, if desired, the system 5 can be controlled automatically from a remote point by a centralized traffic control operator in which case the traffic and signal levers would be replaced by appropriate relays having the corresponding contacts and controlled either over a direct wire or over a coded line circuit.

Although I have herein shown and described only one form of apparatus embodying my invention, it is understood that various changes and modifications may be made therein within the 15 scope of the appended claims without departing from the spirit and scope of my invention.

Having thus described my invention, what I claim is:

1. In combination with a stretch of track over 20 which traffic may move in either direction, said stretch being divided into a plurality of track circuit sections, a first and a second manually controlled traffic lever at the first and the second end respectively of said stretch, said levers having a normal and a reverse position for selectively controlling the polarity of the current supplied to said track circuit sections to thereby authorize eastbound and westbound traffic movements respectively, an eastbound and a westbound polarized code following track relay for each of said track circuit sections, said eastbound relay responding only to current of one polarity and said westbound relay responding only to current of the other polarity in any given track circuit section, an eastbound and a westbound source of current for each of said track circuit sections, said westbound track relays and westbound sources being ineffective under eastbound traffic conditions and becoming effective when 30 westbound traffic conditions are established over the stretch, coding means effective when said second traffic lever is moved to its normal position for supplying coded current of the proper polarity from the associated eastbound source to the rails of the last eastbound section to thereby cause code following response of the eastbound track relay for that section, means controlled by said last eastbound track relay for supplying coded polarized current to the rails of the adjoining section from the eastbound source associated therewith to thereby operate the eastbound code following track relay for said adjoining section and in turn to relay the polarized coded current to the first eastbound section for operating the 35 first eastbound code following track relay, an eastbound headblock signal, a lever for said signal, and means controlled by said signal lever when said first traffic lever is in its normal position and said first eastbound track relay is following code for clearing said eastbound headblock signal.

2. In combination with a stretch of track over 40 which traffic may move in either direction, said stretch being divided into a plurality of track circuit sections, a first and a second manually controlled traffic lever at the first and second end respectively of said stretch, said levers having a normal and a reverse position for selectively controlling the polarity of the current supplied to said track circuit sections to thereby authorize eastbound and westbound traffic movements respectively, an eastbound polarized coded track circuit for each of said sections including an eastbound polarized code following track relay, a 45 westbound polarized coded track circuit for each

of said sections including a westbound polarized code following track relay, the rails of each of said sections being common to said eastbound and westbound track circuits and the polarity of the coded track circuit current being opposite in any of said sections according as eastbound or westbound traffic conditions are established therethrough, means effective when said second lever is moved to its normal position for energizing said eastbound track circuits with polarized coded current progressively from said second to said first end of the stretch, an eastbound headblock signal, a lever for said signal, and means controlled by said signal lever and the first eastbound track circuit and effective when said first lever is moved to its normal position for clearing said eastbound headblock signal.

3. In combination with a stretch of track over which traffic may move in either direction, said stretch being divided into a plurality of track circuit sections, a first and a second manually controlled traffic lever at the first and second end respectively of said stretch, said levers having a normal and a reverse position for selectively controlling the polarity of the current supplied to said track circuit sections to thereby authorize eastbound and westbound traffic movements respectively, an eastbound and a westbound signal lever and an eastbound and a westbound headblock signal at the respective ends of said stretch, an eastbound polarized track circuit for each of said sections including an eastbound polarized code following track relay, a westbound polarized coded track circuit for each of said sections including a westbound polarized code following track relay, the rails of each of said sections being common to said eastbound and said westbound track circuits and the polarity of the coded track circuit current being opposite in any of said sections according as eastbound or westbound traffic conditions are established therethrough, means effective when said second traffic lever is moved to its normal position for setting said westbound headblock signal at stop and for energizing said eastbound track circuits progressively from said second to said first end of the stretch with polarized coded current, means effective when said first traffic lever is moved to its normal position and said eastbound signal lever is operated for clearing said eastbound headblock signal, means effective when said first traffic lever is moved to its reverse position for setting said eastbound headblock signal at stop and for energizing said westbound track circuits progressively from said first to said second end of the stretch with polarized coded current, and means effective when said second traffic lever is moved to its reverse position and said westbound signal lever is operated for clearing said westbound headblock signal.

4. In combination with a stretch of track over which traffic may move in either direction, said stretch being divided into a plurality of track circuit sections, an eastbound and a westbound polarized code following track relay for each of said track circuit sections, each of said relays being normally connected across the rails of its associated section and being oppositely polarized in any given section, means effective when traffic conditions are established in the eastbound direction for alternately disconnecting the westbound track relay associated with the last eastbound section and supplying an impulse of current of the proper polarity to said last section to thereby cause code following operation of the eastbound track relay for said last section, means

controlled by said last-named eastbound track relay for alternately disconnecting the westbound track relay of the adjoining section and supplying an impulse of polarized current to said adjoining section to cause code following operation of the associated eastbound track relay and to relay polarized coded track circuit current to the rails of the first section to operate the first eastbound code following track relay, an eastbound headblock signal, and means effective when said first eastbound track relay is following code for clearing said eastbound headblock signal.

5. In combination with a stretch of track over which traffic may move in either direction, said stretch being divided into a plurality of track circuit sections, an eastbound and a westbound polarized code following track relay for each of said track circuit sections, each of said relays being normally connected across the rails of its associated section, the eastbound and westbound relays associated with a given section being oppositely polarized, manually controllable means at the eastbound exit end of the stretch for supplying coded current of proper polarity to the last eastbound track circuit of said stretch for causing code following operation of the eastbound track relay associated therewith, means controlled by said last-named track relay for progressively relaying polarized coded current to the remaining sections of said stretch to finally cause code following operation of the eastbound track relay for the first track circuit section, and manually controllable means at the eastbound entering end of the stretch for clearing the eastbound headblock signal and for preventing the supply of polarized coded current of a polarity such as would operate said westbound polarized code following track relays.

6. In a two-direction single track signaling system having opposing headblock signals at the ends thereof, a track circuit junction between said opposing signals, an eastbound and a westbound polarized code following track relay normally connected across the rails on opposite sides of said track circuit junction respectively, means for supplying polarized coded current to the track circuit associated with said eastbound relay to cause code following operation thereof, and means effective when said eastbound relay is following code for alternately disconnecting said westbound relay from the track and substituting a source of current therefor to thereby supply polarized coded current to the rails associated with said westbound relay.

55. In a two-direction single track signaling system having at least two adjoining track circuits between the ends of the single track stretch, an eastbound and a westbound polarized code following track relay normally connected across the rails of said two adjoining track circuits respectively, means for supplying polarized coded current to one of said track circuits, and means effective when one of said relays is following said coded current for alternately disconnecting the other of said relays from the track and substituting a source of current therefor to thereby relay coded current into the other of said track circuits.

70. In a two-direction single track signaling system having at least two adjoining track circuits between the ends of the single track stretch, an eastbound and a westbound polarized code following track relay normally connected across the rails of said two adjoining track circuits respectively, means for supplying polarized coded cur-

75. In a two-direction single track signaling system having at least two adjoining track circuits between the ends of the single track stretch, an eastbound and a westbound polarized code following track relay normally connected across the rails of said two adjoining track circuits respectively, means for supplying polarized coded cur-

rent to one of said track circuits, and means effective when one of said relays is following said coded current for alternately disconnecting the other of said relays from the track and connecting a track circuit source of opposite polarity to that which would operate said other relay to thereby relay coded current into the other of said track circuits.

9. In a two-direction single track signaling system having at least two adjoining track circuits between the ends of the single track stretch, an eastbound and a westbound polarized code following track relay normally connected across the rails of said two adjoining track circuits respectively, means for supplying polarized coded current to one of said track circuits to cause said eastbound track relay to follow code, an eastbound home relay which remains energized whenever said eastbound track relay is following code, a coding relay energized over a front contact of said home relay, said coding relay having a back contact included in the track connection of said westbound track relay, and means including a front contact of said coding relay for supplying polarized coded current to the other of said track circuits.

10. In a two-direction single track signaling system having at least two adjoining track circuits between the ends of the single track stretch, an eastbound and a westbound polarized code following track relay normally connected across the rails of said two adjoining track circuits respectively, means for supplying polarized coded current to one of said track circuits to cause said eastbound track relay to follow code, an eastbound home relay which remains energized whenever said eastbound track relay is following code, a coding relay, a first energizing circuit for said coding relay including a front contact of said home relay for causing said coding relay to operate at a first code rate, a second energizing circuit for said coding relay including a back contact of said home relay and effective when and only when eastbound traffic conditions have been established over said stretch for causing said coding relay to operate at a second code rate, said coding relay having a back contact included in the track connection of said westbound track relay, and means including a front contact of said coding relay for supplying polarized coded current to the other of said track circuits.

11. In a two-direction single track signaling system having at least two adjoining track circuits between the ends of the single track stretch, an eastbound and a westbound polarized code following track relay normally connected across the rails of said two adjoining track circuits respectively, means for supplying polarized coded current to one of said track circuits to cause said eastbound track relay to follow code, an eastbound home relay which remains energized whenever said eastbound track relay is following code, a coding relay, a first energizing circuit for said coding relay including a front contact of said home relay for causing said coding relay to operate at a first code rate, an eastbound directional stick relay, a second energizing circuit for said coding relay including a front contact of said directional stick relay and a back contact of said home relay for causing said coding relay to operate at a second code rate, said coding relay having a back contact included in the track connection of said westbound track relay, and means including a front contact of said coding relay

for supplying polarized coded current to the other of said track circuits.

12. In a two-direction single track signaling system having at least two adjoining track circuits between the ends of the single track stretch, an eastbound and a westbound polarized code following track relay normally connected across the rails of said two adjoining track circuits respectively, means for supplying polarized coded current to one of said track circuits to cause said eastbound track relay to follow code, a checking relay which remains energized whenever said eastbound track relay is following code, the energizing circuit for said checking relay including a back contact of said westbound track relay, an eastbound home relay which remains energized whenever said eastbound track relay is following code, the energizing circuit for said home relay including a front contact of said checking relay, a coding relay, an eastbound directional stick relay, a first energizing circuit for said coding relay including a front contact of said home relay for causing said coding relay to operate at a first code rate, a second energizing circuit for said coding relay including a front contact of said directional stick relay and a back contact of said home relay for causing said coding relay to operate at a second code rate, said coding relay having a back contact included in the track connection of said westbound track relay, and means including a front contact of said coding relay for supplying polarized coded current to the other of said track circuits.

13. In a two-direction single track signaling system having at least two adjoining track circuits between the ends of the single track stretch, an eastbound and a westbound polarized code following track relay normally connected across the rails of said two adjoining track circuits respectively, a coding relay for each of said track circuits, each coding relay having a back contact included in the track connection of its associated track relay, and means effective when either of said track relays is following code for causing operation of its associated coding relay to thereby supply polarized coded current over a front contact thereof to the adjoining track circuit.

14. In a two-direction single track signaling system having at least two adjoining track circuits between the ends of the single track stretch, an eastbound and a westbound polarized code following track relay normally connected across the rails of said two adjoining track circuits respectively, means for supplying polarized coded current to one of said track circuits to operate the track relay associated therewith, and means effective when said associated track relay is operating for periodically and alternately disconnecting the other track relay from the track and connecting a source of polarized current across the rails of the other of said track circuits.

15. In a two-direction single track signaling system, a track circuit at the entering end of the stretch of single track for a given direction of traffic movement, a polarized code following track relay normally connected across the rails of said track circuit, a headblock signal at said entering end controlled by said track relay, means for supplying polarized coded current to said track circuit to cause operation of said track relay, a traffic lever and a signal lever, a decoding relay having an energizing circuit which includes a front contact of said track relay and a contact of each of said two levers, and means including

a front contact of said decoding relay for clearing said headblock signal.

16. In a two-direction single track signaling system, a track circuit at the leaving end of the stretch of single track for a given direction of traffic movement, a polarized code following track relay normally connected across the rails of said track circuit, a leaving signal at said leaving end, a home relay for said signal, a coding relay, a traffic lever, means including a front contact of said home relay and a contact of said traffic

lever for causing operation of said coding relay at a first rate, means including a back contact of said home relay and said contact of the traffic lever for causing operation of said coding relay at a second rate, and means including a contact of said coding relay for supplying polarized coded current to the rails of said track circuit to thereby operate said polarized code following track relay.
